EARRING

Ralph Pintarelli, 83 Waterman Ave., Johnston, R.I.

Filed Dec. 16, 1963, Ser. No. 77,819

Term of patent 14 years

(Cl. D45—9)

Fig. 1

Fig. 2

Fig. 3

Fig. 4

Fig. 5

FIG. 1 is a front elevational view of an earring showing my new design;

FIG. 2 is a rear elevational view thereof;

FIG. 3 is a side edge view thereof;

FIG. 4 is a top edge view thereof; and

FIG. 5 is a bottom edge view thereof.

The dominant features of my design reside in the full-line portions of the drawing.

The broken line showing of the pendant has been omitted from FIGS. 4 and 5 for convenience of illustration.

I claim:

The ornamental design for an earring, substantially as shown and described.
